UNITED STATES PATENT OFFICE.

HARRY DALITZ, OF CLEVELAND, OHIO, ASSIGNOR TO J. C. HIPP, OF CLEVELAND, OHIO.

DESIGN FOR A GAS-HEATER.

59,199.

Specification for Design.

Patented Oct. 4, 1921.

Application filed May 16, 1921. Serial No. 470,017. Term of patent 14 years.

To all whom it may concern:

Be it known that I, HARRY DALITZ, a citizen of the United States, residing at Cleveland, in the county of Cuyahoga and State of Ohio, have invented a new, original, and ornamental Design for a Gas-Heater, of which the following is a specification, reference being had to the accompanying drawing, forming part thereof, in which—

Figure 1 is a plan view and Fig. 2 a side elevation of a gas heater, showing my new design.

I claim:

The ornamental design for a gas heater, as shown.

HARRY DALITZ.
